DESIGN FOR AN AIRPLANE

Leo E. Oliver, Sanger, Calif.

Application October 21, 1944, Serial No. 115,908

Term of patent 14 years

(Cl. D71—1)

To all whom it may concern:

Be it known that I, Leo E. Oliver, a citizen of the United States, residing at Sanger, in the county of Fresno and State of California, have invented a new, original, and ornamental Design for an Airplane, of which the following is a specification, reference being had to the accompanying drawing, forming a part thereof.

In the drawing:

Figure 1 is a top plan view of an airplane, showing my new design;

Figure 2 is a side elevational view of the air-

plane showing the landing gear in retracted position;

Figure 3 is a front end elevational view of the airplane likewise showing the landing gear in retracted position.

Figure 4 is an enlarged fragmentary cross section on line 4—4 of Figure 2.

I claim:

The ornamental design for an airplane, as shown.

LEO E. OLIVER.
